UNITED STATES PATENT OFFICE.

JAMES E. KELSO, OF ROCHESTER, NEW YORK.

NAPPING MACHINE.

Application filed September 29, 1927. Serial No. 222,794.

This invention relates to a machine for restoring the nap of fabrics, such for example, as blankets, and has for its principal object the provision of a device which will operate 5 efficiently and with a minimum of wear and tear on the fabric.

Another object of the invention is to provide a machine in which the peripheral speed of a napping roll is so related to the speed of 10 travel of the fabric that the nap is restored in a satisfactory manner without wearing away a substantial part of the fabric, as is done in machines heretofore known.

A further object of the invention is to provide a napping machine with novel mechanism for adjusting one napping roll with respect to another roll, so as to vary the space 15 between the rolls in order to accommodate fabrics of different thicknesses.

An additional object of the invention is to provide a generally improved napping machine in which there is practically no discharge of lint, and which will operate more satisfactorily than any of the devices here- 20 tofore used.

With these and other ends in view, the invention comprises the structure and combination of parts which will appear more clearly from the following description when 25 read in conjunction with the accompanying drawings, the novel features being pointed out in the claims following the description.

In the drawings:

Figure 1 is a plan illustrating one possible embodiment of the machine;

Figure 2 is a front elevation thereof;

Figure 3 is an elevation of the left hand end of the machine;

Figure 4 is a cross-section taken centrally 40 through the machine, illustrating the napping rolls, the feeding roll, the fabric guiding means, and a piece of fabric being fed through the machine;

Figure 5 is an elevation of the right hand 45 end of the machine, and

Figure 6 is a sectional view taken approximately on the line 6—6 of Figure 3, illustrating the construction of a movable bearing to permit adjustment of one of the napping 50 rolls.

It is well known to those acquainted with the behavior of fabrics such as woolen blankets that wear and various causes, such as washing, result in flattening the nap so 55 that it lies down against the body of the fabric instead of standing out. Various means

have been proposed heretofore to restore the nap, but all of these means, so far as known, have defects of one kind or another. According to the present invention, however, mechanism is provided which will restore the nap satisfactorily and quickly, without loss of material or damage to the fabric.

In one possible embodiment of the invention, illustrated in the drawings accompanying this application, there is provided at each end of the machine a framework comprising vertical members 11 and 12, which constitute the legs on which the machine rests, and which are connected to each other at their tops by suitable cross pieces such as 13. At each end of the machine, and somewhat below the top cross piece 13, is a supporting member 14, which may be in the nature of a horizontally disposed angle iron. Journalled in 70 suitable bearings 15 fixed to the supporting members 14 near the front of the machine, is a shaft 16 carrying a napping roll 17. This napping roll, as illustrated in Figures 3 and 4, is of cylindrical form, and consists essentially of a cylindrical base on which are secured large numbers of fine wires extending radially outward from the base. These wires are intended to be all of the same length so that their outer ends are all equi-distant from 85 the axis of the cylinder.

On each of the supporting members 14, and slightly behind the bearing 15, is a movably mounted bearing 21, best illustrated in Figures 3 and 6. These bearings are so arranged 90 that they may be slid longitudinally along the supporting members 14. As shown in Figure 6, each bearing comprises a portion 22 in engagement with one of the flanges of the supporting members 14, another portion 23 in contact with the other flange of the supporting member, and a portion 24 extending around and embracing the free edge of one of the flanges on the supporting member. As will be readily apparent from Figure 6, this 100 construction holds the bearing from transverse displacement and yet permits it to move longitudinally along the supporting member.

In these movable bearings 21 is journalled a shaft 26 carrying a second napping roll 27 105 similar in all respects to the napping roll 17 above described. This napping roll, as will be seen from Figure 3, is parallel to and slightly spaced from the first napping roll. The mounting of the second roll in movable 110 bearings permits this roll to be moved bodily toward or away from the first napping roll,

and thus allows adjustment of the space between the two rolls.

In order to move the adjustable napping roll bodily, various means might be employed. 5 In the embodiment here shown, a resilient member such as the spring 30 is attached at one end to each of the movable bearings 21, and at the other end to a part of the framework of the machine. These resilient members 30 exert a constant pull tending to move the bearings 21 and the napping roll 27 in a direction away from the first napping roll 17.

To oppose this tendency and to hold the roll 27 at the desired distance from the roll 17, means may be employed, such as the links 31, one end of each link being pivotally connected to the movable bearing 21, and the other end being connected to an arm 32 on a shaft 33 extending along the front of the machine, as shown especially in Figures 2 and 3. Another arm 34 may be fixed to this shaft, and to this arm may be secured a threaded member 35, as shown in Figure 3, on which is placed a nut 36 having a hand wheel 37 formed thereon.

It is obvious from an inspection of the drawings that rotation of the hand wheel 37 in the proper direction will draw the threaded member 35 so as to turn the shaft 33 in a clockwise direction, when viewed as in Figure 3. This will result in moving the arms 32 to draw the links 31 so as to move the bearings 21 against the tension of the resilient member 30. Thus the roll 27 may be brought as close as desired to the roll 17.

Mounted in suitable bearings somewhat above the napping rolls 17 and 27, there may be provided a feeding roll 40 for feeding the fabric at the desired rate through the machine, and provided with fine wires for engagement with the surface of a blanket, the same as the napping rolls and as shown in Figure 4. In order to force the fabric to pass between the two napping rolls, and to prevent it from clinging to the face of the feeding roll, guiding means such as the belts 41 may be employed. In the embodiment here shown, a member 42 is placed parallel to the axis of the rolls, and slightly away from the periphery of the feeding roll, as shown in Figure 4. The belts 41, which may be strings or bands, extend around the feeding roll 40 and the member 42, as clearly shown in the drawings, and as the feeding roll turns, the belts 41 move with it and slide over the member 42. It will be understood that a number of these belts 41 are spaced at intervals throughout the length of the feeding roll, as indicated in Figures 1 and 2.

60 Additional guiding means may be used to insure that the fabric shall travel in the right direction. For instance, a member such as a rod or stiff wire 43 (Figures 3 and 4) may be placed below the napping rolls, and wires 44 may be stretched at intervals between the

members 42 and 43. Similarly, other rods 45, 46, and 47 may be fixed to the frame of the machine, and wires 48 may be stretched over these rods.

From this construction it will be seen that as the fabric is fed along by the feeding roll 40, the guiding means 41 prevents it from adhering to the surface of the roll and forces it to the left of the member 42, when viewed from the direction of Figure 4. The guiding wires 44 and 48 then serve to guide the fabric into the space between the two napping rolls 17 and 27, and the lower ends of these wires guide the fabric as it emerges from the rolls and keep it from becoming wound around either one of them.

To drive the feeding roll and the napping rolls, any suitable arrangement may be employed. For instance, a driving shaft 50 may be journalled near the bottom of the machine, this shaft being driven in any desired manner. As shown in Figure 5, this driving shaft 50 may have a sprocket 51 fixed thereto which, by means of a chain 52, may drive a sprocket 53 on the shaft 16 of the napping roll 17. 90 This shaft 16 may carry also a spur gear 54 meshing with a similar gear 55 on the shaft 26 of the other napping roll 27. It will be recalled from the foregoing description that the roll 27 is movable bodily toward or away from the roll 17. It should be understood, however, that this adjusting movement, in practice, is of comparatively slight extent, and the spur gears 54 and 55 may therefore be constructed with teeth sufficiently long so 100 that they will mesh effectively when the napping rolls are so placed as to have either the maximum or minimum spacing between them.

The feeding roll 40 may be driven, for example, in the manner shown in Figure 3. A 105 sprocket 56 may be fixed to the shaft 16 and may drive, through the chain 57, a sprocket 58 on the shaft of the feeding roll. It will be noted from the drawings that the sprocket 56 is of smaller diameter than the sprocket 110 58, and therefore the feeding roll will rotate at a slower rate than the napping roll. Furthermore, the feeding roll is of somewhat less diameter than the napping roll, and therefore, the peripheral speed of the feeding roll 115 for any given speed of rotation will be less than it would be if the feeding roll were of the same diameter as the napping roll. Hence, it is apparent that the rate of travel 120 of the fabric when fed forward by the feeding roll will be somewhat less than the peripheral speed of the napping rolls.

In the machines heretofore commonly used, the roll corresponding to the napping rolls of the present machine has been rotated 125 at a very high rate of speed with respect to travel of the fabric. This has resulted in giving a more or less burnishing action to the rolls, and it has worn away a considerable part of the surface of the fabric. In fact, in 130

some machines it has been necessary to provide fans or other means for removing the large quantities of lint worn away from the surface of the fabric.

5 As distinguished from this burnishing action in prior machines, which damages the fabric to a considerable extent, the machine constructed according to the present invention brushes lightly and gently over the surface of the fabric and raises the nap effectively without wearing away any considerable portion of the material. It is not necessary to provide fans or any other mechanism for removing lint, because there is practically no lint produced in the operation of this machine.

One reason for the distinctly superior results produced by this machine is the comparatively slow rotation of the napping rolls with respect to the travel of the fabric. There is nothing like the burnishing and wearing away action of the prior machines, but instead, the napping rolls rotate very slowly in comparison to the rolls heretofore known, and only slightly faster than the feeding travel of the fabric. In the machine illustrated in the drawings, the sizes of the sprockets and the diameters of the rolls have been so proportioned that the peripheral speed of the napping rolls is about 3.6 times the rate of feed of the fabric. This proportion is intended to be merely by way of illustration and not as an absolute value which must necessarily be used. The invention contemplates wide variations in the ratio of napping roll speed to feeding roll speed, and it should be understood that the use is contemplated of any speed which will lift the nap without removing any of it and wearing away the fabric.

Another reason for the superior results obtained by the present machine is the fact that the napping rolls may be adjusted so as to have between them a clear space slightly less than the thickness of the fabric being operated upon. Furthermore, the fabric is held in contact with each of the rolls only by the pressure applied to it by the other roll. Since the fine wires forming the working surface of the rolls are somewhat flexible, the surface is slightly resilient, and therefore the fabric is held yieldingly against the surface of the napping rolls. This results in a more gentle action of the rolls, which raises the nap better and has practically no tendency to wear away the fabric. In the machines heretofore commonly used, the fabric has been held in contact with the napping roll by a hard, unyielding member, and this has been one of the reasons why the napping roll had a harsh, clawing action on the fabric, and wore it away.

By rotation of the hand-wheel 37 above described, the spacing of the napping rolls may be varied from time to time so as to give

the best possible results on each different thickness of fabric run through the machine. The clear space between the rolls should ordinarily be slightly less than the thickness of the fabric, so that the ends of the wires 70 on the rolls will not dig deeply into the fabric, but will simply brush lightly over the surface of it, in order to lift the nap and cause it to stand out in the manner desired.

To hold the fabric conveniently while it is being fed through the device, a trough 60 may be attached to the front of the machine, and a feed board 61 may be placed above it, near the feed roll 40. The use of this feed board, as well as the action of the machine 75 upon the fabric, is clearly illustrated in Figure 4. It will be seen that the layer of fabric 62 is led up from the trough 60, over the edge of the feed board 61, and along the top surface of the board to the feed roll 40. 80 Here it is caught by the rotating roll and moved along. The belts 41 and the wires 44 and 48 serve to guide the fabric into the space between the two napping rolls 17 and 27. The ends of the fine wires on these rolls are 85 moving slightly faster than the fabric, and they brush lightly over opposite sides thereof, raising the nap on both sides. The fabric then emerges from the rolls with the nap restored, as indicated at 63. 90

While one embodiment of the invention has been disclosed, it is to be understood that the inventive idea may be carried out in a number of ways. This application is therefore not to be limited to the precise details shown, 100 but is intended to cover all modifications thereof falling within the spirit of the invention or the scope of the appended claims.

I claim:

1. In a napping machine, the combination 105 with a napping roll, of a second napping roll parallel to and spaced from said first roll, a feeding roll parallel to and spaced from said napping rolls, said napping rolls being rotatable at a slightly greater peripheral speed 110 than that of said feeding roll, a plurality of spaced members parallel to said napping rolls and between them and said feeding roll, a guiding belt extending around said feeding roll and one of said members, and guiding 115 means extending from each of said members in such a direction as to guide a piece of fabric from said feeding roll to said napping rolls so as to cause it to pass through the space between said rolls. 120

2. In a napping machine, the combination with a plurality of substantially parallel supporting members, of a bearing movable along each of said supporting members, a shaft journalled in said movable bearings, a napping roll carried by said shaft, resilient means 125 tending to move one of said bearings in one direction, a shaft substantially perpendicular to said supporting members, a plurality of arms on said shaft, connecting members con- 130

necting each of said movable bearings with one of said arms, and means for moving said arms so as to draw said movable bearings in a direction opposite to that in which said resilient means tends to move them.

3. A blanket napping machine comprising a pair of napping rolls each having yieldable blanket engaging wires and disposed in the same horizontal plane and a feeding roll having yieldable blanket engaging wires, the feeding roll being disposed above the napping rolls and operating to feed and suspend a blanket in a vertical plane directly from the feeding roll to the napping rolls.

4. A blanket napping machine comprising a pair of napping rolls each having yieldable blanket engaging wires and arranged in the same horizontal plane, the wires on one napping roll being spaced from the wires on the other roll slightly less than the thickness of a blanket, and a feeding roll located above the napping rolls and having blanket engaging wires for feeding a single blanket from a point above the rolls downwardly between the napping rolls while suspended in a vertical plane.

5. A blanket napping machine comprising a pair of napping rolls each having yieldable blanket engaging wires and arranged in a horizontal plane with the wires on one napping roll spaced from the wires on the other napping roll slightly less than the thickness of a blanket, and a blanket feeding roll having yieldable blanket engaging wires and arranged above the napping rolls and operable to feed a single blanket directly to the napping rolls while suspended in a vertical plane therebetween.

6. A blanket napping machine comprising a pair of napping rolls each having yieldable blanket engaging wires and arranged in the same horizontal plane and operable to lift the nap of a blanket simultaneously on both sides thereof, and a blanket feeding roll having yieldable blanket engaging wires for feeding a single blanket downwardly between the napping rolls, the peripheral speeds of the napping rolls and the arrangement of feeding roll and napping rolls being such that the nap on both surfaces of a single blanket can be raised at a single operation without removing any substantial part of the nap.

7. In a blanket napping machine, the combination with a napping roll having yieldable blanket engaging wires, of a second napping roll having yieldable blanket engaging wires which are spaced from the wires on the first mentioned roll slightly less than the thickness of a blanket, and a feeding roll located above the napping rolls and having yieldable blanket engaging wires acting to feed a single blanket downwardly between the napping rolls.

8. In a blanket napping machine, the combination with a napping roll having yieldable

blanket engaging wires, of a second napping roll having yieldable blanket engaging wires and spaced from the first named roll in the same horizontal plane, and a feeding roll located above the napping rolls and having yieldable blanket engaging wires acting to feed a blanket downwardly between the napping rolls, said blanket being freely suspended between the napping rolls by the feeding roll and held in contact with the wires of each of said napping rolls by the pressure of the wires on the other napping roll.

9. In a blanket napping machine, the combination with a blanket feeding roll having yieldable blanket engaging wires, of a pair of napping rolls each having yieldable blanket engaging wires and arranged in a horizontal plane beneath the feeding roll to receive therebetween a blanket suspended in a vertical plane by the feeding roll, a supporting member, a bearing slidable along the supporting member, one of the napping rolls being journaled in said bearing, means constantly tending to move said bearing in a direction away from the blanket, and adjustable means opposing said tendency whereby said napping roll may be finely adjusted toward a blanket while the latter is suspended by the feeding roll.

10. In a blanket napping machine, the combination with a blanket feeding roll having yieldable blanket engaging wires, of a pair of napping rolls each having yieldable blanket engaging wires and arranged in a horizontal plane beneath the feeding roll to receive a blanket suspended from the feeding roll in a vertical plane, one of said napping rolls being bodily movable horizontally, means constantly tending to move said roll bodily away from the blanket, and adjustable means opposing said tendency of the roll to move bodily whereby said roll may be finely adjusted toward a blanket suspended from said feeding roll.

11. In a blanket napping machine, the combination with a napping roll having yieldable blanket engaging wires, of a second napping roll having yieldable blanket engaging wires and bodily movable in the same horizontal plane toward and away from said first napping roll, resilient means tending to move the second roll away from the first roll, adjustable means for opposing said resilient means whereby the second napping roll may be held in any adjusted position with respect to the first roll, and a feeding roll having yieldable blanket engaging wires and located above the napping rolls for suspending and feeding a blanket downwardly between the napping rolls.

12. In a blanket napping machine, the combination with a napping roll having yieldable blanket engaging wires, of a second napping roll having yieldable blanket

engaging wires and arranged parallel to and spaced from the said roll in the same horizontal plane, a feeding roll having yieldable blanket engaging wires and located above the napping rolls, the feeding roll being rotatable at a peripheral speed slightly less than that of the napping rolls, and means for guiding a blanket from the feeding roll to the napping rolls so that the blanket as it leaves the feeding roll can move freely 10 downwardly between the napping rolls.

In witness whereof, I have hereunto signed my name.

JAMES E. KELSO.
